[57] CLAIM

The ornamental design for a apron assembly, as shown and described.

DESCRIPTION

FIG. 1 is a front plan view of the apron assembly of the present invention;

FIG. 2 is a back plan view of the apron assembly of FIG. 1; FIG. 3 is a left side plan view of the apron assembly of FIG. 1;

FIG. 4 is a right side plan view of the apron assembly of FIG. 1;

FIG. 5 is a top plan view of the apron assembly of FIG. 1; and,

FIG. 6 is a bottom plan view of the apron assembly of FIG. 1.

The straps in FIGS. 1, 2, 5, and 6, shown broken away for ease of illustration are of indeterminate length.
